pinch, thus firmly securing the overlapping side portions in closed position. Then by pulling up on the top end of the lace and swinging it toward one end of the strap, the slack of the fastener is drawn to the top inside the boot and there held by friction under the strap.

The boot is also provided with loops by which it may be pulled on to the feet, as indicated at 18.

The top of the boot is a closed annular portion, or tube, 14, of considerable depth. For example, in the semi-high boot it is about one-fifth the height of the complete boot but may be higher if desired. It is intended to fit snugly, but not too tightly to the calf of the leg of the wearer, and in any case to be large enough to allow the foot of the wearer to pass through it easily.

To put the boot on, the lace is pulled downward at the upper end until the button, 16, is stopped by the strap, 15. Then the lace, 13 is unwound from the stud or pinch, 17, which allows enough slack to permit the lace to be unhooked from the hook fasteners, 12. This loosens the lace so that it may slide easily through the eyelets in the eyelet fasteners, 12', and allow those on the front side portion to separate from those on the rear side portion, leaving the boot free to bulge at the slit.

At this stage the boot is ready to be put on. The foot of the wearer may be slipped through the tubular top and as it reaches the slit portion of the leg of the boot, the latter will spread open to give plenty of room for the foot to pass down to its position in the foot of the boot. When the foot of the wearer is in place, it is only necessary to pull on the lace to draw together the rear and front side portions where the eyelet hooks are arranged. The lace is then hooked over the hook fasteners, drawn tight and wound around the stud or pinch. The button, 16, on the upper end of the lace, 13, may be drawn up to take up the slack, and then pulled laterally to pinch the lace at one end of the strap where it fits tightly against the inside of the boot top.

It is obvious that the boot can be put on in a

very short time. In case of a sudden emergency it is not even necessary to stop to run the lace around the hooks of the hook fasteners, because the lace is held to the boot at both ends and cannot drag on the ground.

In the best embodiment of the invention, each hook fastener has its back curved inward transversely to reinforce the hook, as shown in the drawing, and the point of the hook is curved upward at the extreme end to make it easier to slip the lace into place beneath the hook.

Furthermore, in order to make the boot substantially water-tight, a collapsible tongue, 19, (Fig. 7), inside the slit portion of the boot, may be provided, this tongue consisting of a strip of soft leather having its vertical edges secured to the rear side portion and to the front side portion, the lower end of the tongue being secured to the toe portion whereby water cannot flow through the slit into the interior of the boot. The tongue is creased along the vertical central line so it may fold down flat on the inside of the boot.

The boot may be made up from pieces of leather in various forms.

What is claimed is:

A boot having an entirely closed annular top portion, one slit side formed by a front side portion and a rear side portion arranged to overlap each other, said slit terminating at the lower edge of the said top portion where the upper portions of said front and rear side portions are secured, a series of fasteners secured to the rear side portion, another series secured to the front side portion, a single lace secured at its lower end to the boot and arranged to pass zig-zag over the respective fasteners in the two series and through a hole in the lower part of the annular top to the inside of said top, a strap secured to the inside of the said annular top beneath which the upper portion of the lace passes, a button on the free end of the lace and a pinch fastener device secured near the upper end of the slit around which the lace may be locked.
